UNITED STATES PATENT OFFICE.

WILLIAM SPARKS, OF JACKSON, MICHIGAN, ASSIGNOR TO THE SPARKS-WITHINGTON COMPANY, OF JACKSON, MICHIGAN, A CORPORATION OF OHIO.

FUEL-FEEDING DEVICE.

Application filed March 12, 1920. Serial No. 365,232.

To all whom it may concern:

Be it known that I, WILLIAM SPARKS, of Jackson, in the county of Jackson, in the State of Michigan, have invented new and useful Improvements in Fuel-Feeding Devices, of which the following, taken in connection with the accompanying drawings, is a full, clear, and exact description.

This invention relates to certain improvements in fuel feeding systems, and is particularly applicable for supplying fuel from a low level tank to the carburetor of an internal combustion engine, constituting a part of an automobile, motor boat, aero-15 plane, or the like.

The main object of the invention is to provide a fuel supply apparatus or system of comparatively simple construction that does not have any of the objectionable features of the gravity feed system, the pressure feed system or the commonly used vacuum system.

Other objects and advantages relate to the details of construction and operation of the device, as will more fully appear from the following description taken in connection with the accompanying drawings, in which:

Figure 1 is an elevation of the apparatus 30 associated with a low level tank and an internal combustion engine.

Figure 2 is a vertical cross-section through the tank, and the operating device for effecting elevation of liquid fuel from the low level tank.

As illustrated, the apparatus comprises a tank —1— which may consist of a cylindrical wall —2—, and upper and lower caps, —3— and —4— respectively, the lower caps 40 being penetrated by pipe —5— for supplying liquid fuel by gravity to the carburetor —6— of an internal combustion engine —7—. The upper cap —3— is penetrated by a lateral tubular extension —8—, from an elongated cylinder —9— within which cylinder is positioned a reciprocating piston —10—, preferably as shown, of substantially cup-shaped form, to provide an elongated bearing surface. The cap —11— is 45 adapted for threaded relation with a nipple —12— having a relatively small conduit —13— for supplying motive fluid to the cylinder —9— from one of the combustion chambers of the engine, and for this purpose nipple —12— is connected by pipe

—14— with one of the engine cylinders. The closed end —15— of the cylinder —9— may be provided with a circular recess —16— within which one of the end coils of spring —17— expands to lock the spring to 60 the wall of the cylinder. The piston —10— in like manner is formed with a circular recess —18— within which the other end coil of the spring —17— expands to lock the spring to the piston.

The cylinder —9—, preferably adjacent the end —15— is in communication with pipe —19— leading to a low level tank —20— and being preferably provided at some point along its length with a non-return check valve —21— adapted to prevent back flow of liquid fuel to the tank —20— after each liquid elevating stroke of piston —10— as effected by spring —17—. This valve —21— may be of any suitable 75 and well-known construction and as shown, is an ordinary ball valve. The lateral extension —8— as shown terminates in an elbow shaped nipple —22— having its open lower end normally closed by a flat valve 80 —23—. However, other shapes and forms of nipple may be used and other well known constructions of valves to suit the form and shape of the nipple. Preferably, however, the valve is a normally closed one.

The operation of the structure so far described will be readily understood.

The compression from the engine is supplied to cylinder —9— through conduit —13— and will force the piston —10— toward the end —15— of the cylinder compressing the spring —17—. The spring should be of sufficient strength and of such length and form as to prevent the piston from striking the end —15— of the cylinder. When the compression is relieved, the spring —17— will move the piston in a reverse direction within the cylinder, the valve —23— will be closed both by gravity and suction and the vacuum produced within the cylinder will open valve —21— and affect the elevation of liquid fuel into the cylinder and the lateral tubular extension —8—. Upon the next stroke of piston —10— effected by compression transferred from the engine cylinder, the valve —23— will be opened and the liquid fuel discharged into the tank —1—, the valve —21— preventing back-flow of the liquid through the pipe —19—.

The spring —17— should be of sufficient length and of such form and strength as to permit piston operation under both high and low compression as produced in the engine cylinder. Such a form of spring is readily determined by experiment.

In order to prevent flooding of the tank —1— when the engine is not consuming liquid fuel as fast as the same would be 10 elevated by the device shown and forced into the tank, a float —24— is provided mounted upon a lever —25— pivotally carried within the tank —1—, the opposite arm —26— of the lever being so formed, shaped 15 and positioned, that it will contact with and move valve —23— from its seat when a pre-determined level of liquid is reached in tank —1— and as shown, the lever is pivoted at —27— to the lower end of the nipple —22— 20 and the arm —26— is shaped in the form of a cam which is adapted to contact with valve —23— when the float is moved to a pre-determined position by liquid fuel in tank —1—. Any further rise of the float 25 as affected by rise of level of the fuel will open the valve —23— gradually in direct ratio with the rise of the level of the fuel so that the vacuum produced by operation of piston —10— will be partially or entirely 30 neutralized by air or liquid drawn from tank —1—, and no further elevation of liquid from tank —20— will take place until a pre-determined reduction of the level 35 of the fuel in tank —1— takes place. The tank —1— is maintained under atmospheric pressure by a vent —28—.

It will be noted that the cylinder —9—, the lateral extension —8— and nipple —22— may, if desired, be formed of a single

casting, and that as shown, the nipple —22— 40 discharges into the reservoir above the normal level of the liquid therein, so that when valve —23— is opened by float —24—, the operation of piston —10— is rendered ineffectual by air entering the cylinder from tank —1—, rather than by a surging back and forth of the liquid fuel.

Although I have shown and described a particular construction, form and arrangement of apparatus, I do not desire to limit 50 myself to the same, as various changes may be made in the details of form, arrangement and construction without departing from this invention as set forth in the appended claim.

What I claim is:—

A fuel supply system for internal combustion engines comprising a reservoir, an elongated piston chamber, a conduit leading from said chamber to a source of liquid fuel supply, an elbow-shaped nipple communicating with the piston chamber and extending downwardly into the reservoir, and terminating in a laterally directed opening, a valve movably secured to said nipple and movable laterally to open and close the discharge opening in the nipple, a float stem pivoted on the lower end of said nipple and having a part adapted to contact with said valve to move the same laterally away from the nipple and a float mounted on said stem.

In witness whereof I have hereunto set my hand this 24th day of February, 1920.

WILLIAM SPARKS.
